Primary Examiner — Selina Sikder

(57) **CLAIM**

The ornamental design for a controller for interventional surgery robot, as shown and described.

DESCRIPTION

1. Controller for interventional surgery robot

1.1 : Perspective

1.2 : Front

1.3 : Back

1.4 : Left

1.5 : Right

1.6 : Top

The product is a component of an interventional surgery robot, which is used for advancing and retreating, attitude adjustment and positioning of a puncture needle.

1 Claim, 6 Drawing Sheets
